UNITED STATES PATENT OFFICE.

ALONZO GHENT, OF HELIX, OREGON.

HOISTING AND HANDLING MACHINE.

1,267,756.

Specification of Letters Patent. Patented May 28, 1918.

Application filed November 12, 1917. Serial No. 201,591.

To all whom it may concern:

Be it known that I, ALONZO GHENT, a citizen of the United States, residing at Helix, in the county of Umatilla and State of Oregon, have invented certain new and useful Improvements in Hoisting and Handling Machines, of which the following is a specification, reference being had to the accompanying drawings.

- 10 This invention relates to hoisting appliances, and particularly to means for hoisting objects such as barrels, bales, boxes, and the like, and so that they may be readily handled.
- 15 The general object of the invention is to provide a mechanism of this character whereby an article may be hoisted to any convenient height, and then rotated in either direction, and then again lowered so that either 20 end of the article may be disposed upon the ground.

A further object of the invention is the provision of means particularly adapted for handling barrels of gasolene or like containers, which may be readily operated, requires but little power and by which the barrel may be lifted from the ground, turned so as to present either head upward, the faucet inserted in the container and the 30 barrel or container again rotated and lowered in position for use.

A further object of the invention is the provision of a device of this character in which there is a winding shaft with a cable 35 adapted for the purpose of hoisting the article, and a shaft for rotating the article, and means whereby an operating crank may be operatively connected either to the winding shaft or to the shaft for rotating the 40 article.

A further object is to provide a hoisting device of this character in which the shaft for rotating the article is detachably engaged by a hoisting hook, in turn operatively 45 connected to the winding shaft, to provide seats for the first named shaft, which will support this shaft with the article slung above the ground, and provide means for operatively connecting the shaft for rotating 50 the article with a hand-operated driving means.

A further object is to provide in connection with the mechanism above referred to, a detachable gin pole adapted to support a 55 cable and pulley, the cable being adapted to be connected to the hoisting or winding

shaft, and in this connection, generally speaking, to provide a hoisting and handling device which may be used for handling barrels, or other articles, in the manner here- 60 fore described, and which also may be used as a loading machine, or hoisting machine having a relatively great range of movement.

Other objects will appear in the course 65 of the following description.

My invention is illustrated in the accompanying drawings, wherein:

Figure 1 is a side elevation of my im- 70 proved handling machine;

Fig. 2 is a front elevation thereof;

Fig. 3 is a section on the line 3—3 of 75 Fig. 1;

Fig. 4 is a fragmentary perspective view showing the means for holding the shaft 24 in its shifted position;

Fig. 5 is a perspective view of one of the barrel clamps;

Fig. 6 is a perspective view of the other barrel clamp; 80

Fig. 7 is a perspective view of the chain tightener;

Fig. 8 is an end view of the sprocket wheel 26; and

Fig. 9 is an end view of the gear wheel 28. 85

Referring to these figures, it will be seen that the frame of the hoisting machine comprises the uprights 10, which are disposed in parallel relation to each other and are connected by a cross bar 11. These uprights 90 10 and the cross bar are preferably integral and made of T-iron. The uprights 10 rest upon longitudinally extending sills 12, which are preferably made of angle iron, the vertical flanges 13 of the angle iron being riveted to the lateral flanges of the up- 95 rights. Braces 14 are preferably riveted to the flanges of the T iron, and to the flanges of the angle iron, and convergent braces 15 are preferably attached to the inner webs 100 of the vertical supports 10 and extend upward to the middle of the cross bar.

Mounted adjacent the upper ends of the uprights 10 are the outwardly projecting brackets 16, which are riveted or otherwise 105 attached to the T iron, these brackets at their ends being formed with bearings for a transverse winding shaft 17, this winding shaft carrying upon it a relatively large sprocket gear wheel 18. Disposed at any 110 suitable height on the upright 10, below the brackets 16, are brackets 19, which are verti-

2
cally slotted as at 20, and form seats or bearings for a shaft 21, which I will hereafter designate as the tilting shaft. This shaft 21 carries upon it a gear wheel 22,

5 and the end of the shaft is formed with a collar or shoulder 23, which engages on the outside of the adjacent supporting bracket 19.

For the purpose of rotating the winding shaft 17, and rotating the tilting shaft 21, I 10 provide a shaft 24, which is longitudinally shiftable through one of the supports 10 and through the corresponding bracket 19, this shaft carrying upon it a crank handle 25 whereby the shaft may be rotated. Loosely 15 mounted upon this driving shaft 24 is a sprocket wheel 26 having a relatively small diameter and over which passes a sprocket chain 27 which extends around the sprocket wheel 18. Also loosely mounted upon the 20 shaft 24 is a gear wheel 28, which meshes with the gear wheel 22 on the tilting shaft 21.

Projecting from the shaft 24 is a pin 29 disposed between the gear wheel 28 and the 25 sprocket wheel 26, and the gear wheel 28 and the sprocket wheel 26 are both provided with radial notches or recesses 29^a into which the pin 29 is adapted to engage when the shaft 24 is shifted in one direction or the 30 other. When engaged with the gear wheel 28, this gear wheel will be rotated while the sprocket wheel 26 will remain idle and when the pin is in engagement with the sprocket wheel 26, the gear wheel will remain idle.

35 Mounted upon the adjacent upright 10 is a latch 30, having a lug 31 adapted to be inserted between the head 32 of the crank and the edge of the support 10, when the crank shaft 24 has been shifted to engage the pin 40 29 with the gear wheel 28. This latch is pivotally supported at its upper end by means of a pin, a coil spring 33 surrounding this pin and forcing the latch inward. The inner end of the shaft 24 is supported by 45 means of a brace 34. For the purpose of holding the sprocket chain in driving engagement with the sprocket wheels 18 and 26, I provide a chain tightener comprising a yoke 35, which embraces the chain 27, this 50 yoke having a roller 36 and the yoke being mounted upon an arm 37 forming part and projecting from a coil spring 38 mounted upon a pin 39. Any other form of chain tightener may be used, however. The hoisting shaft 17 carries at one end the ratchet wheel 40, which is adapted to be engaged by a locking pawl 41 mounted on the adjacent upright 10, this locking pawl preventing a 55 reverse rotation of the hoisting shaft.

60 Mounted upon the tilting shaft 21 is a sprocket wheel 42, and engaging with the shaft 21 and embracing the sprocket wheel is a clevis 43. Attached to an eye 44 on the cross bar 11 is a cable 45, which extends 65 downward and passes through a pulley 46

and then extends upward and is attached to the hoisting shaft in any suitable manner, this pulley 46 having a hook 47 detachably engaging with the clevis 43.

A chain, preferably a sprocket chain, 48 70 passes over the sprocket wheel 42, and this chain carries at its opposite ends article clamping means. I have illustrated the device as being adapted particularly for hoisting cylindrical containers or barrels, and for 75 this purpose, one end of the sprocket chain 48 carries upon it a clamping hook 49 adapted to engage with the rim of a barrel and having a set screw 50, which will lock over the flange of the rim and hold the clamp in 80 firm engagement therewith. At the opposite end of the barrel, I preferably provide a barrel end clamping device comprising three arms pivotally connected to each other. Two of these arms 51 are formed with hooks 85 52 at their ends and are relatively short. The other arm 53 is relatively long and is formed with a hooked end 54 and with a handle 55, whereby it may be manipulated. The upper end of this arm is bent over the 90 pivot 56 for the arms to form a hook 57 with which the extremity of the sprocket chain 48 is adapted to be engaged.

The operation of this part of my invention is as follows: Assuming that it be desired to 95 handle a metallic container of the usual type for containing gasoline, then this barrel or container is disposed between the uprights 10 extending parallel to the sills 12. The clevis 43 is disengaged from the hook 47. The 100 hook 49 is engaged with one end of the container and the clamping members 51 and 53 are engaged with the other end of the container. The chain 48 is then engaged with the hook 57. The crank handle 45 is then 105 rotated to lower the hoisting hook 47, which is engaged with the clevis 43. The crank handle is then rotated in the reverse direction to cause the winding up of the hoisting shaft 17, the pin 29 being, of course, engaged 110 with the sprocket wheel 26, but disengaged from the gear wheel 28. When the tilting shaft 21 has been lifted to a position above the brackets 19, the crank handle is reversely turned so as to lower the tilting shaft into 115 the seats or slots 20. If now it be desired to tilt the container, the crank shaft 24 is shifted laterally to carry the pin 29 into engagement with the gear wheel 28, disengaging it from the sprocket wheel 26. Now 120 upon a rotation of the shaft 24 in either direction, the tilting shaft will be rotated, rotating the sprocket wheel 42 and tilting the barrel in either direction desired. Thus, for instance, the barrel may be tilted so as to 125 carry the bung-hole upward and then a faucet may be disposed within the barrel, the barrel tilted back to its vertical position, the tilting shaft operatively disconnected from the driving shaft 24, and then the driv- 130

ing shaft rotated to lower the barrel onto the floor or to the ground. The clamps may then be, of course, readily disconnected from the barrel, and the empty barrel is rolled 5 away and the full one put in its place.

By the use of the device as above described, a small boy can handle a 50 gallon barrel of gasoline and he can also take down an empty barrel and replace the full 10 one without any assistance. It will be seen that this hoisting mechanism provides for a ready and easy handling of the barrels or containers and that the containers may be handled without losing any gasoline therefrom. Furthermore, it will be seen that by 15 providing the pawl 41 engaging the ratchet 40, that the tilting shaft may be held at any desired level, while supporting a full container and it will also be seen that the container may be swung around a vertical axis or shifted rearward or forward with relatively slight effort to that the container may be readily put in place.

While I have especially referred in the 20 above description to barrels or containers holding gasoline, it will be obvious that the device may be used for boxes, bales, or other articles and that it is not limited to the use above described.

30 While I have illustrated a form of my invention which, as before stated, has been found very effective in practice, yet I do not wish to be limited to the details of construction shown or to the exact arrangement of 35 parts, as it is obvious that many changes may be made, within the scope of the appended claims.

Having described my invention, what I claim is:—

40 1. A hoisting mechanism comprising a supporting frame including uprights and a cross bar, a winding shaft mounted on the frame, a tilting shaft, a cable on the winding shaft operatively engaging the tilting shaft 45 to raise or lower it, means on the tilting shaft for engaging the article to be handled, seats carried by the supporting frame for the tilting shaft, means for rotating the driven shaft to raise or lower the tilting 50 shaft, and means for rotating the tilting shaft to tilt an article supported thereby.

2. A hoisting device of the character described comprising a supporting frame, a winding shaft mounted thereon, a hoisting 55 cable on the winding shaft, a tilting shaft having a sprocket wheel thereon, means on the hoisting cable for detachably engaging the tilting shaft, said means permitting the tilting shaft to rotate, an article engaging 60 sprocket chain passing over the sprocket wheel, and means on the frame for rotating either the hoisting shaft or the tilting shaft.

3. A hoisting mechanism of the character described comprising a supporting frame, a 65 hoisting shaft thereon, a cable engaged by

the hoisting shaft, a tilting shaft, supporting brackets mounted on the frame, and upon which the tilting shaft is adapted to rest and rotate, the tilting shaft being removable from the supporting brackets, means 70 on the cable for operatively engaging the tilting shaft, said means permitting the tilting shaft to rotate, a sprocket wheel on the tilting shaft, a sprocket chain passing thereover, article clamping devices carried by 75 the chain, and means whereby the hoisting shaft may be rotated to raise or lower the tilting shaft or whereby the tilting shaft may be rotated when disposed upon said brackets to thereby tilt the supported article 80

4. A hoisting device of the character described comprising a supporting frame including parallel uprights, a hoisting shaft rotatably mounted adjacent the upper end of the frame, a sprocket wheel thereon, a cable wound upon the hoisting shaft, a driving shaft carrying a sprocket wheel, a chain engaging the sprocket wheel on the driving shaft of the first named sprocket wheel, brackets extending from the uprights, a tilting shaft, means detachably connecting the tilting shaft with the cable, said tilting shaft being detachably but rotatably supported on 85 said brackets, a sprocket wheel mounted on the tilting shaft, a sprocket chain passing 90 over the sprocket wheel and engageable with an article to be hoisted, and tilted, and means for engaging the driving shaft with the sprocket wheel thereon or operatively engaging the driving shaft with the tilting 95 shaft to cause a rotation of the latter when it is disposed on said brackets.

5. A hoisting device of the character described comprising a supporting frame including parallel uprights, a hoisting shaft 100 rotatably mounted adjacent the upper end of the frame, a sprocket wheel thereon, a cable wound upon the hoisting shaft, a driving shaft carrying a sprocket wheel, a chain engaging the sprocket wheel on the driving 105 shaft of the first named sprocket wheel, brackets extending from the uprights, a tilting shaft, means detachably connecting the tilting shaft with the cable, said tilting shaft being detachably but rotatably supported on 110 said brackets, a sprocket wheel mounted on the tilting shaft, a sprocket chain passing over the sprocket wheel and engageable with an article to be hoisted and tilted, and means for engaging the driving shaft with the 115 sprocket wheel thereon or operatively engaging the driving shaft with the tilting shaft to cause a rotation of the latter when it is disposed on said brackets, said means

120 including a gear wheel on the tilting shaft, a gear wheel loose on the driving shaft, and means on the driving shaft for engaging either the sprocket wheel thereon or the gear wheel thereon.

6. A hoisting device of the character de- 130

- scribed comprising uprights and a transverse cross bar, brackets mounted adjacent the upper ends of the uprights, a hoisting shaft rotatably mounted in the brackets and carrying a sprocket wheel, a cable engaged with the cross bar at one end and wound upon the hoisting shaft, a pulley supported by said cable and having a hook, a driving shaft mounted on one of the uprights and carrying a sprocket wheel, a cable engaged with the cross bar at one end and wound upon the hoisting shaft, a pulley supported by said cable and having a hook, a driving shaft mounted on one of the uprights and carrying a loose sprocket wheel, a sprocket chain passing over both of said sprocket wheels, a chain tightener engaging said chain, means for holding the winding shaft from reverse movement, a gear wheel loosely mounted upon the driving shaft, brackets projecting out from the uprights on a level with said gear wheel, each of said brackets having vertically extending shaft seats open at their upper ends, a tilting shaft adapted to be supported in said seats and carrying a sprocket wheel, a gear wheel mounted on said shaft and engageable with the gear wheel on the driving shaft when the tilting shaft is in said seats, a chain passing over said sprocket wheel on the tilting shaft and adapted to be engaged with an article to be hoisted and tilted, and means whereby the driving shaft may be engaged either with the sprocket wheel thereon or with the gear wheel thereon.
7. A hoisting device of the character described comprising uprights and a transverse cross bar, brackets mounted adjacent the upper ends of the uprights, a hoisting shaft rotatably mounted in the brackets and carry-
- ing a sprocket wheel, a cable engaged with the cross bar at one end and wound upon the hoisting shaft, a pulley supported by said cable and having a hook, a driving shaft mounted on one of the uprights and carrying a loose sprocket wheel, a sprocket chain passing over both of said sprocket wheels, a chain tightener engaging said chain, means for holding the winding shaft from reverse movement, a gear wheel loosely mounted upon the driving shaft, brackets projecting out from the uprights on a level with said gear wheel, each of said brackets having vertically extending shaft seats open at their upper ends, a tilting shaft adapted to be supported in said seats and carrying a sprocket wheel, a gear wheel mounted on said shaft and engageable with the gear wheel on the driving shaft when the tilting shaft is in said seats, a chain passing over said sprocket wheel on the tilting shaft and adapted to be engaged with an article to be hoisted and tilted, means whereby the driving shaft may be engaged either with the sprocket wheel thereon or with the gear wheel thereon, and means for preventing an accidental disengagement of the driving shaft from its gear wheel.

In testimony whereof I hereunto affix my signature in the presence of two witnesses. 65

ALONZO GHENT.
